Cooper, Kerr & Denham

UNITED STATES PATENT OFFICE.

JOHN S. MAXWELL, OF RICHMOND, INDIANA, ASSIGNOR TO STARR PIANO COMPANY, OF RICHMOND, INDIANA, A CORPORATION OF INDIANA.

PNEUMATIC ACTION.

Application filed August 25, 1925. Serial No. 52,309.

This invention relates to pneumatic player pianos and similar musical instruments, and refers more particularly to valves for pneumatic actions.

6 The object of this invention is to produce a valve which is of light construction so as to be susceptible of having its position changed immediately whenever there is a variation of pressure on its diaphragm, and 10 which will, at the same time, be capable of seating firmly on its seat even though its stem be inclined at an angle from the plane of the valve seat or that the same is unlikely to be seated tightly for any other 15 cause, such as, for example, an inclined valve seat.

The valve seats in the actions are pressed or threaded into place, and it is probable that some of these might not assume the 20 act true position intended, that is, of having its seat in a horizontal plane perpendicular to the natural position of the valve stem. In such a case, if the valve and valve stem were rigidly connected, binding might 25 result and the general efficiency of the instrument could be seriously affected. Binding, however, would not occur in the usual case, but a lack of complete seating of the valve on its seat might result, which would allow 30 a leakage of air that would entail the expenditure of more power than should be necessary in the operation of the piano.

Heretofore, valves have been used that would allow for a universal adjustment and 35 flexible connection between a valve stem and valve that would permit the valve to seat truly even though the seat be at an angle with the horizontal and the valve assume different positions on each subsequent seating 40 due to any rotary displacement, and it is part of my purpose of invention, as outlined above, to produce a simple form of valve capable of universal adjustment between the valve and valve stem with a minimum 45 number of parts and amount of material which will possess the desired qualities of lightness and flexibility and be capable of effective sealing.

Other objects and uses of the invention 50 will appear from a detailed description of the same, which consists in the features of construction and combinations of parts hereinafter described and claimed.

In the drawings,

Fig. 1 is a transverse fragmentary view 55 of an action showing the valve in its normal position.

Fig. 2 is a perspective view from the under side of the valve.

Fig. 3 is a section of the valve and valve 60 stem.

In Fig. 1 the valve is shown in its normal position in an action, and it comprises a disk or head 10 having a projection 11 extending from its upper surface and passing 65 through a facing 12 of leather, fiber, or other suitable material. The lower face of the disk has raised from its center, or integral therewith, a button 13. To the lower face is glued or otherwise caused to adhere another facing 70 14 which extends over and covers the button forming a smooth rounded rise at the center, Fig. 2. The stem of the valve may be of any design and the one which I have chosen to illustrate has a central portion 15 which has a cross-section of slightly 75 greater area than the button on the disk, but it is desirable only that these two features have approximately the same area. Four flanges 16 extend radially from the 80 central portion 15 of the stem, but any other arrangement could be used. In assembling the valve and valve stem the central portion of the top of the stem is glued directly to the leather facing on the lower surface of 85 the valve in such a position that the center of the button is in alignment with the axis of the stem. It is evident that, owing to the height of the button from the valve face and its hemispherical contour, the stem will 90 be susceptible to being inclined in any direction from the perpendicular or, in other words, from a normal to the plane of the valve face.

Another essential and most desirable feature is to have some amount of flexibility and springiness between the stem and the valve as well as universal adjustment, and I have obtained excellent results in this direction by gluing the leather facing on the 100 lower side of the valve at its edges only and not having any close adherence between the button or the face immediately surrounding the button with the facing. This condition allows for pivotal motion of the stem 105 in respect to the valve without any tendency to cause a separation of the stem from the leather facing, Fig. 3. When the stem

is at an angle with the valve the leather on one side of the button may be slightly lifted from contact with the valve face, but the main contacting glued area will not be 5 disturbed.

I have used leather as a facing because of its excellent sealing qualities due to its pliability and consequent ability to settle and fill any irregularities in the valve seat, 10 and also because it does away with the necessity of having any other cushion or resilient connection between the valve and the stem. The leather lends itself to such alternate stretching and compressing during the operation of the valve as it may be called upon 15 to submit to, but I do not wish to be limited to this material since any other material capable of performing the same function could be used.

20 The valve is shown in its normal position on seat 17. When a hole in the music roll passes over the opening in the tracker bar related to any particular action, air is admitted to chamber 18 and the resulting un- 25 balanced pressure on diaphragm 19 causes the valve to be raised so that its upper fac- 30 ing 12 contacts the valve cap 20 and closes the port 21 thereby shutting off communica- 35 tion with the atmosphere of passage 22 and causing the bellows to collapse and actuate the note striking arm in the manner well known in the art.

The diaphragm 19 comprises a normally dish-shaped member of light construction 35 which may be made of rubber, fibre, leather, or of any other air tight flexible material. It has a flanged edge 23 which bears upon and is secured to ledge 24 and when the dia- 40 phragm is in a position of rest, its central portion extends downwardly within a recess or chamber. To the central portion of the diaphragm is attached a pressure distribu- 45 tor or equalizer 25 in the form of a disk and preferably made from a single piece of ma- 50 terial so as to insure rigidity and simplicity as well as lightness. At the center of the pressure distributor there is a rounded pro- 55 jection in the form of an indentation 26 the lowest extent of the outer surface of the pro- 60 jection of which is attached to the dia- phragm by means of glue, cement, a pin, or otherwise fastening. The rounded surface allows for tilting movement in any vertical 65 plane between the pressure distributor and the diaphragm so that the upper surface of the distributor will seek the plane of the lower end of the valve stem when the dia- phragm is raised by air pressure. This 70 action will occur even though the valve stem be very much inclined from its normal vertical position. In order to cushion the 75 contacting effort of the valve-stem and pressure distributor, a thin cushion 27 of soft fibrous material is secured to the pressure dis- 80 tributor at its center. It is of larger dimen- 85

sion than the largest cross-sectional dimen- 90 sion of the valve-stem, and is sufficiently thin that a space remains between it and the valve-stem when the parts are in the positions illustrated in Fig. 1.

70 It is evident from the foregoing description that the connection between the valve-head and the valve-stem, and the relation of the valve-stem to the pressure distributor, and the connection between the pressure distributor and the diaphragm, are such as to insure perfect and instant operation of the pneumatic due to the universal adjustability of the valve parts, the lightness and simplicity of their construction, and their mechanically efficient design which permits of complete seating and accurate registry of the correlated parts.

80 These improvements are susceptible to 85 variations in structure and shape, and I do not wish to be limited to the particular form described, for I contemplate the use of other suitable materials than those recited, and such alterations and modifications as may be deemed expedient and coming 90 within the scope of the appended claims.

95 What I claim is—

1. A valve comprising a head, a stem, and a resilient facing intermediate said head and stem, said head having a projection directly above said stem.

100 2. A valve comprising a head having a raised portion at its center, a facing extending over said raised portion, and a stem affixed to said facing opposite said raised portion.

105 3. A valve comprising a head having a raised portion at its center, a facing extending over the surface of said valve and said raised portion, and a stem affixed to the outer surface of said facing at a point opposite said raised portion.

110 4. A valve comprising a head having a raised portion at its center and integrally therewith, a facing secured to the valve face around said raised portion and overlying said raised portion, and a stem affixed to the outside surface of said facing opposite said raised portion.

115 5. A valve comprising a head having a raised portion, a facing affixed to the surface of said valve so as to allow parting of said valve and facing at a definite place, and a stem secured to the outer surface of said facing opposite said definite place.

120 6. A valve comprising a disk having a substantially hemispherical button projecting from its surface, a facing extending over said button and surface, and a stem affixed to said facing opposite said button, said stem having a cross-sectional end surface of relatively greater area than said button.

125 7. A valve comprising a disk having a substantial hemispherical button projecting

from its surface, a facing extending over said button and affixed to the surface around said button, and a stem having one end affixed to said facing opposite said button 5 whereby said stem may be tilted in respect to said disk.

8. In an action for player pianos, the combination of a valve comprising a head, a stem, a pressure distributor having a projection at its center, and a diaphragm secured to said pressure distributor. 10

9. In an action for player pianos, the combination of a valve comprising a head, a stem, a facing connecting said valve and 15 stem, a pressure distributor having a projection, a diaphragm secured to said pressure distributor at the highest point of said projection, and means intermediate said stem and pressure distributor for cushioning the effort of impact. 20

10. In an action for player pianos, the combination of a valve, a button on said valve, a facing overlying said button and forming the sole connection between said 25 stem and said valve, and a diaphragm disposed at the opposite end of said stem and spaced therefrom.

11. In an action for player pianos, the combination of a valve, a stem flexibly con-

nected to said valve, a diaphragm, a pressure distributor flexibly connected to said diaphragm and spaced from said stem, the flexible connection permitting of relative rocking motion of said disk and pressure distributor. 30

12. In an action for player pianos, the combination of a valve, a stem flexibly connected to said valve, a disk having a rounded projection integral therewith, a diaphragm secured to said projection so as to permit tilting between said diaphragm and said disk, and means on said disk for contacting the end of said stem. 35

13. A valve comprising in combination a head, a stem, an actuating diaphragm, and a disk spaced from said stem and independent thereof and secured to said diaphragm at a single point of less area than the area of said disk. 40

14. A valve comprising in combination, a head, a stem, an actuating diaphragm, and a disk having a raised portion contacting said diaphragm, said disk being intermediate said diaphragm and said stem and free from connecting relation with said stem. 45

In testimony whereof I hereto affix my signature.

JOHN S. MAXWELL.
